SINK STOPPER

Maurice H. Kraines, Los Angeles, and Robert L. Unkrich,
Long Beach, Calif.; said Unkrich assignor to said
Kraines

Filed Dec. 26, 1961, Ser. No. 68,059

Term of patent 14 years

(Cl. D91—1)

Fig. 1

Fig. 2

The bottom is substantially plain.

We claim:

The ornamental design for a sink stopper, substantially as shown and described.
